UNITED STATES PATENT OFFICE.

PAUL HAUSER, SR., AND ROBERT H. DEPEW, OF ST. PAUL, MINNESOTA.

MALT-TURNING APPARATUS.

SPECIFICATION forming part of Letters Patent No. 390,299, dated October 2, 1888.

Application filed April 16, 1888. Serial No. 270,762. (No model.)

To all whom it may concern:

Be it known that we, PAUL HAUSER, Sr., and ROBERT H. DEPEW, both citizens of the United States, and both residing at St. Paul, 5 in the county of Ramsey and State of Minnesota, have jointly invented certain new and useful Improvements in Malt-Turning Apparatus, of which the following is a specification.

This invention relates to machines or apparatus for turning malt in malt houses, kilns, and similar locations; and it consists in the construction, combination, and arrangement of parts, as hereinafter shown and described, and specifically pointed out in the claims.

15 In the drawings, Figure 1 is a sectional side elevation. Fig. 2 is a cross-sectional view on the line $x-x$ of Fig. 1, with the driving mechanism removed. Fig. 3 is an enlarged cross-sectional detail of one of the armed turning 20 rollers and brushes, illustrating more fully the details of the construction.

A' represents the floor of the malt house or kiln, having curved upturned ends A^2 , and with tracks A^3 along the upper edge of its sides 25 A^4 . Only one of the sides A^4 is shown in Fig. 1; but the two sides will be precisely alike, and will each be provided with its own track A^3 , as shown in Fig. 2.

B' represents frames suspended from the 30 tracks A^3 by grooved rollers B^2 , and adapted to support a shaft, B^3 , preferably formed of gas or other tubing to secure strength and lightness. Each of the tracks will be provided with one of the frames B' , so that each end of 35 the shaft B^3 will be properly supported and adapted to be carried back and forth over the floor A when the frames B' are moved back and forth along the tracks.

Upon opposite sides of the shaft B^3 boards 40 D are secured in sections, the edges of the boards being armed with curved metal blades a , and with sections of brushes E , pivotally connected to the shaft between the sections of boards D , as shown. The edges of the blades 45 a do not quite touch the floor A' when the shaft B^3 is revolved; but the brushes are adapted to come in contact with the floor, so that the thin layers of the malt, which the blades fail to reach, will be swept up by the brushes.

50 The sections of the boards D will be arranged in progressive angular positions, so that the

blades a will act one at a time upon the malt and lift only a small portion at a time, no two of the blades being in operation at the same time. By this means the strains upon the shaft 55 are greatly reduced, enabling a longer shaft to be employed without a center support. The brushes E are also arranged in sections, as shown, each brush being one-half the length of the sections of the boards D and not opposite each other, as shown, so that the brushes are in operation only one-half as much as the blades a , which is sufficient to accomplish the desired results. The brushes will be long enough to rest on the edges of the boards D or 60 the backs of the blades a , as shown in Figs. 1 and 3, when thrown from side to side, the pivoting of the brushes being a very important feature of our invention.

When the shaft B^3 is revolved and drawn 70 across the malt floor or kiln, at the same time the blades a , as before stated, each gathers up a small quantity of the malt and elevates it over the shaft and deposits it on the other side. This action causes the brushes to be dragged 75 across the floor, as shown in Fig. 1, and sweep the floor clear of the malt which the blades a do not reach, and, being carried upward and over the shaft by the revolution of the latter until they are past the center of gravity of said 80 shaft they (the brushes) will suddenly fall over and strike the floor with considerable force and produce a sweeping effect upon the malt next the floor, while at the same time the falling of the brushes suddenly increases the weight on 85 the side of the shaft opposite to the active side of the blades a , and greatly assists the latter in elevating its load of malt and decreases the power required to revolve the shaft. The brushes thus adapt themselves to the inequalities of the floor, and do not exert a lifting force, as they would if they were rigidly attached to the shaft; but exert a sweeping force, which sweeps the lower strata of the malt forward, so that it may be caught by the blades 90 a and elevated over the shaft. The action of the brushes when thus arranged is very effective and complete, enabling every particle of the malt to be picked up and elevated over the shaft, and thus "turned" every time the 95 shaft is drawn back and forth over the floor.

The blades and brushes are shown arranged

to act both when the shaft is being drawn backward and forward over the floor, the brushes acting all the time, while only one-half of the blades are active at the same time.

5 On the faces of the boards D, between the blades *a*, are arranged double-inclined plates D', whose function it is to cause the malt when falling from the blades *a* to be thrown backward away from the shaft upon the mass of the 10 malt just turned, and not fall down again beneath the shaft. This is also an important feature of our invention, and effectually prevents any tendency of the recently-turned malt to fall beneath the shaft again and come in 15 contact with the unturned malt.

The mechanism for moving the shaft B back and forth along the tracks and revolving it at the same time is the same as that shown in our application for a patent, Serial No. 251,505, 20 filed October 5, 1887.

The edges of the blades *a* will be formed with teeth *a'*, which serve to separate the particles of the "sprouts" from the malt and disconnect adhering masses.

Having thus described our invention, what 25 we claim as new is—

1. In a malt-turning apparatus, the combination of a revolving shaft, blades having curved edges and secured upon opposite sides of said shaft, and brushes pivoted upon opposite sides of the shaft in the spaces between the curved edges of said blades, substantially as described. 30

2. In a malt-turning apparatus, the combination of a revolving shaft, blades secured upon opposite sides of said shaft, and formed with curved edges *a* and double-inclined plates or central portions, D', between the inner faces of said blades, substantially as described. 35

In testimony whereof we have hereunto set 40 our hands in the presence of two subscribing witnesses.

PAUL HAUSER, SR.
ROBERT H. DEPEW.
